FISHING LURE

William D. Storm, 625 N. Finalay, Norman, Okla.

Filed Aug. 14, 1964, Ser. No. 81,286

Term of patent 14 years

(Cl. D31—4)

FIG. 1

FIG. 2

FIG. 3

FIG. 4

FIG. 1 is a side elevation of a fishing lure showing my new design;

FIG. 2 is a top plan view thereof;

FIG. 3 is a front view thereof with portions omitted for convenience of illustration; and

FIG. 4 is a rear view thereof.

The dominant features of my design reside in the portions shown in full lines.

I claim:

The ornamental design for a fishing lure, as shown and described.
